NO. 710

John North
Design for Drawing Divid
Patented May 29, 1855—

John North, of Middletown, Conn.
Letters Patent No. 710. Dated May 29th 1855.

The schedule referred to in these Letters Patent, and making part of the same

To all to whom these presents shall come

Be it known, that I, John North, of Middletown, in the County of Middlesex, and State of Connecticut, have invented a design

for sewing bird, & that the following is a full, clear, and exact description of the principle, & character which distinguishes it from all other things before known, and of the usual manner of making, modifying, and using the same, reference being had to the accompanying drawings.

Fig. 1. a side view of my design.

Fig. 2. detached parts of the jaws for holding the work.

As a matter of taste, and in good keeping with the objects wrought for, in the sewing birds now so extensively introduced, I have conceived the following design. I mount a strong bird a upon a strong perch b, b' and this perch turns upon an axis c . The foremost part b of this perch or foot piece forms the upper portion of a bill or jaw and the rear portion b' bears some resemblance to a crest. Under the portion b is the lower part of a bill or jaw b^2 attached to the stand d . The spring e fixed to the stand at e' keeps the jaws closed by pressure under the crest b' . The portions b, b', b^2 together with the axis c which correspond to an eye, forms the figure of a head of strength, having jaws, mandibles or bill of proportions consistent with the duty it is to perform viz. seizing and holding the work and at the same time does not mar the image of the bird.

It is common in works of this description to cause the work to be held by some part of the ornamental figure surmounting the pedestal. These figures are usually too frail for the purpose, are often broken and are for the most part distorted to accommodate them to their office. The special configuration of the bird and of the head for holding the cloth may be varied without changing the main feature of my design as above set forth, in which the integrity of the bird is preserved and the cloth or work held by the parts of the perch or foot piece and action of the spring thereon, these parts being fancifully designed as above set forth.

What I claim as my invention is, the design for sewing bird as herein set forth.
